UNITED STATES PATENT OFFICE.

LEWIS S. GRAHAM, OF NEW ORLEANS, LOUISIANA.

DESIGN FOR A PAMPHLET-COVER.

SPECIFICATION forming part of Design No. 22,147, dated January 24, 1893.

Application filed December 5, 1892. Serial No. 454,174. Term of patent 7 years.

To all whom it may concern:

Be it known that I, LOUIS SPENCE GRAHAM, a citizen of the United States, residing at New Orleans, in the parish of Orleans and State 5 of Louisiana, have invented certain new and useful Improvements in a Design for Advertising; and I do declare the following to be a full, clear, and exact description of the invention, such as will enable others skilled in the 10 art to which it appertains to make and use the same.

My invention is a design for a pamphlet cover, and it will be fully understood from the 15 following description when taken in connection with the accompanying drawings, in which: The figure is a face view of a pamphlet cover showing my design.

The leading feature of my design consists 20 of two horns of plenty discharging a number of coins, and a pair of scales, the pans of which are laden with coins. These are arranged in the center of the pamphlet cover as shown; the horns A, which are of a curvilinear form and are ornamented with curvilinear 25 ribs, being arranged in an inverted position across each other, while the scales B, are arranged behind the horns and have their beam resting above the point where the horns intersect each other. The pamphlet cover C, is 30 rectangular in its general contour and is provided adjacent to its edges with a rectangular border a, within which my design is arranged.

Arranged adjacent to the four corners of 35 the border a, and extending from the longitudinal lines to the transverse lines thereof, are the boxes or inclosures D, which are formed by the straight lines b, and are of a rectangular form. These boxes or inclosures

D, are bordered by the straight lines c, arranged between the outer longitudinal lines b, and the corners of the border a, the end lines d, the curved lines e, e', the short inner longitudinal lines f, which extend from the curved lines e', and the short hatch lines g, 45 which extend from the straight lines b, to the lines c, d, e, e', and f, respectively.

Connecting the curved lines e, of the two upper boxes or inclosures D, and the curved lines e, of the two lower boxes or inclosures 50 D, are curved lines h, and connecting the short longitudinal lines f, of the two upper and two lower boxes D, are curved lines i. These lines h, i, are connected at suitable intervals in their length by the short hatch 55 lines j, so as to harmonize with borders of the boxes or inclosures.

Arranged upon the straight lines c, are approximately semi-circular scrolls or ornamentations k, which are bordered by the broken 60 curved lines l, and the straight lines m; and the space between the said curved and straight lines l, m, and the border is filled in as indicated by n.

Situated adjacent to the longitudinal lines 65 of the border a, and the boxes D, are circles p, which are arranged in series parallel to the said longitudinal lines of the border.

Having described my design, what I claim 70 is:—

The design for a pamphlet cover, as herein described and shown.

In testimony whereof I affix my signature in presence of two witnesses.

LEWIS S. GRAHAM.
